UNITED STATES PATENT OFFICE.

HARLEY E. WARD, OF PEMBerville, OHIO.

LIQUID-FUEL BURNER.

Application filed November 30, 1925. Serial No. 72,089.

This invention relates to liquid fuel burners, and particularly to that class of burners utilizing in addition to the fuel, a liquid, such as water, which, when vaporized, breaks up the particles of fuel for obtaining maximum combustion.

Objects of this invention are to provide a fuel burner which is simple in construction, easy to operate, and does not require the complicated and expensive machines heretofore required in many burners of this type; to provide a burner uniquely constructed and which is adapted to the use of crude oil without the formation of obstructing carbon deposits, thereby to obtain approximately perfect combustion and high heating efficiency; and to provide a liquid fuel burner having the new and improved features of construction hereinafter more particularly described.

Species of which this invention is a genus are shown on the accompanying drawings, in which:

Fig. 1 is a top plan view of a burner construction embodying the invention, with the frusto-conically shaped perforated hood and casing removed; Fig. 2 is a vertical, sectional elevation on the line 2—2 of Fig. 1.

The illustrated embodiment of the invention comprises a horizontally disposed metallic plate 1 provided with an upstanding peripheral flange 2, a relatively small flange 3 spaced inwardly from the flange 2, and a central hollow boss 4. Formed on the plate 1 between the flanges 2 and 3 are a series of openings 5 which enable air to be supplied to the burner, and on the inside of the flange 3 is formed a basin or trough to which liquid fuel, such as crude oil, may be supplied from a pipe line 6 having branches terminating in hook shaped end 7 engaging over the edge of the flange 3. The end 7 of the pipe line may be unhooked from the flange 3 by lifting upwardly and outwardly and thereafter may be drawn downwardly through the adjacent opening 5.

Formed on the generator plate 1 between the boss 4 and flange 3 are a plurality of closely spaced upstanding elongate pins or columns 8 which may be integrally formed with the plate 1. The upper ends of the pins 8 may be upset to provide radial flanges 9 and the pins 8 in the operation of the burner are heated to a relatively high temperature and assist in the vaporization

of the water and fuel supplied to the burner. Also formed on the generator plate 1 and in close juxtaposition to the boss 4 is a series of integral elongate pins 10 which are shorter than the pins 8, the shorter pins being approximately one-half the height of the pins 8.

Attached in any suitable manner to the pins 10 is a splash plate 11 having an upstanding peripheral flange 12 and provided with a plurality of radially extending spouts 13. Water is supplied to the splash plate 11 in any convenient manner, or as illustrated, from a conduit 14 which leads from any suitable source of supply and passes upwardly through the hollow boss 4, through the splash plate 11 and terminates in a downwardly extending end portion. Water dropping on the splash plate 11 flows therefrom through the spouts 13 into receptacles 15 in the form of a trapezium. The receptacles 15 are supported in any suitable manner between pins 8 and the pins 10 and serve as catch basins for the water overflowing the splash plate 11. While the catch basins may be used, it has been found that the burner functions satisfactorily without them.

Supported on the generator plate 1 and positioned on the inside of the flange 2 is an outer casing 16 of substantial height and which may be suitably secured to the flange 2 to provide a rigid construction. Formed on the inside of the casing 16 are helical vanes 17 which imparts spiral or circulatory movement to the air admitted to the inside of the casing through the openings 5 so that more efficient combustion will take place. It is to be noted that the upper or top end of the casing 16 is provided with a wall 18 which is formed with an opening 19 so that the passage of heated gases from the burner is constricted and the spurt of flame therethrough creates a suction to draw in air through the openings 5, thus lessening the necessity of a fan or blower for this purpose.

Supported inside of the casing 16 and resting on the generator plate 1 is a frusto-conically shaped hood 20 having numerous closely spaced apertures 21. The hood 20 is somewhat shorter than the casing 16 and completely encloses the pins 8.

In order to drain the oil or water whenever it is desired from the generator plate 1, a duct 22 is connected to the plate 1 adjacent

the boss 4 and a valve 23 operable by means of a stem handle 24 is attached to the duct 22.

For supporting the generator plate 1 a hollow base 25 is provided, and air for the burner is passed through this base, also the pipes 6 and 14 may extend through it. It is to be noted that the bottom 26 of the base 25 is inclined downwardly toward a drain 27 so that any water or oil from the drain duct 22 may be cleaned from the base. It is also to be noted that should the generator plate 1 become flooded it may overflow the flanges 3 and 4 and pass through the apertures into the base 25 and thence to drain pipe 27.

It has been found desirable to mix a small amount of volatile liquid, such as wood alcohol with the water for aiding in the thorough and efficient combustion of the fuel. In starting, therefore, a small amount of gasoline or alcohol may be supplied to the generator plate 1 in any suitable manner as through the conduit 14 and on the generator plate the liquid will spread itself as a film and this may be ignited in any suitable way, as by means of an electric ignitor of a type well known in the art. When a generator plate 1 is heated to a suitable degree the fuel, such as oil, may be introduced through the pipe 6 to the plate, and thereupon the water may be also introduced through the conduit 14 to the splash plate 11.

It is to be understood that the water is merely dropped upon the splash plate and in passing through the receptacles 15 becomes vaporized, or it may drop to the generator plates where it will be vaporized, and upon vaporization diffuses or breaks up the oil particles so that maximum combustion may take place. Although an artificial draught may be necessary for the air drawn through the openings 5, it has been found that the suction created by the outward passage of the gases from the casing 16 draws in a sufficient amount of air for the purpose. It is also to be understood that the elongate pins 8 and 10 serve to radiate and intensify the heat in the region of the splash plate 11 and the generator plate 1 and this aids in the vaporization of the water and the co-mingling of the water vapor and steam.

An outstanding feature of the invention resides in the construction of the fuel supply line 6 which is provided with a hooked end portion. By means of the hooked end portion the line may be conveniently supported on the flange 3 without employing additional attaching means. It will be noted that the line 6 may be quickly disengaged from the flange 3 whenever it is desired, without disturbing or molesting any other portion of the burner, and this is particularly advantageous should the supply

line become clogged with carbon or any other material. It is also to be observed that the end of the supply line 6 is positioned away from the source of greatest heat so that liability of clogging is materially reduced. 70

It has been found that a burner construction as hereinbefore described, obtains practically perfect combustion and eliminates almost entirely the smoke which has usually been found quite objectionable with burners 75 of this character. It will be observed that the compactness of the parts, simplicity of construction and operation, and consequently low cost contribute materially to the production of a most efficient and useful burner. 80

While I have shown and described a construction which is the best form known to me at the present time, it is to be understood that numerous changes to suit the different shapes and sizes of furnace fire boxes in details of construction and arrangement may be effected without departing from the spirit of the invention, especially as defined in the appended claims. 85

What I claim is:

1. In a device of the class described, a generator plate, elongate heat radiating pins on said plate, heat radiating pins shorter than said first named pins disposed centrally on said plate, a splash plate supported on 95 said relatively short pins, and means for dropping a vaporizable liquid on said splash plate, and means for supplying liquid fuel to said generator plate. 90

2. In a device of the class described, as set forth in claim 1, characterized as follows; an outwardly extending flange on said generator plate in spaced relation to the periphery, and a perforated open ended hood enclosing said pins and engaging said flange. 100 105

3. A device of the class described, comprising a generator plate, elongate heat radiating pins on said plate, heat radiating pins shorter than said first named pins disposed centrally on said plate, a splash plate supported on said relatively short pins, means for dropping a vaporizable liquid on said splash plate, means for supplying liquid fuel to said generator plate, an outwardly extending flange on said generator plate in spaced 110 relation to the periphery, a perforated open ended hood enclosing said pins and engaging said flange, and up set end portions on said pins to provide a greater head radiating 115 surface. 120

4. In a device of the character described, a generator plate having a peripheral flange, a casing engaging said flange, elongate upstanding pins on said plate, elongate pins shorter than said first pins and disposed centrally thereof on said plate, a splash plate supported on said relatively short pins, means for dropping a vaporizable liquid on said splash plate, an outwardly extending flange on said generator plate in inwardly 125 130 135

spaced relation to said first flange, and a frusto-conical perforated open-ended hood engaging said last flange and enclosing said pins, and means for supplying liquid fuel to said generator plate.

5. In a device of the class described, a generator plate, upstanding elongate pins on said plate, a splash plate, means for supporting said splash plate above said generator plate, a casing engaging said generator plate, helical vanes on the inside of said casing, and said generator plate being formed with openings adjacent said casing.

10. In a device of the character described, comprising a generator plate having openings adjacent the periphery thereof and a central opening, upstanding elongate heat

radiating pins on said plate, relatively short pins on said plate disposed centrally of said first pins, a splash plate supported on said relatively short pins, means for dropping a vaporizable liquid on said splash plate, an open-ended frusto-conical perforated hood supported on said generator plate and enclosing said pins, a casing engaging said generator plate, a drain duct attached to the under side of said generator plate, a hollow supporting base for said generator plate, and means extending through said base for supplying liquid fuel to said generator plate. 30

In testimony whereof I have hereunto signed my name to this specification.

HARLEY E. WARD.
